(57) **CLAIM**

The ornamental design for a curved body of cheese made of curved precut slices of cheese, as shown and described.

DESCRIPTION

FIG. 1 is a perspective view of a curved body of cheese made of curved precut slices of cheese showing my new design, with the broken away area indicating indeterminate height of the stack such that the stack may contain any number of slices of cheese;

FIG. 2 is a front elevational view thereof;

FIG. 3 is a first side elevational view thereof;

FIG. 4 is a rear elevational view thereof;

FIG. 5 is a second side elevational view thereof;

FIG. 6 is a top plan view thereof; and,

FIG. 7 is a bottom plan view thereof.
